(57) **ABSTRACT**

A cylinder liner for an opposed-piston engine, and corresponding methods of extending engine durability and thermal management therewith, has opposite ends and a bore with a longitudinal axis for supporting reciprocating movement of a pair of opposed pistons. An intermediate portion of the liner extends between the opposite ends and includes an annular liner portion within which the pistons reach respective TC locations. A liner ring is seated in a portion of the bore in the annular liner portion, between the TC locations, for scraping carbon from top lands of the pistons and/or increasing the thermal resistance of the annular liner portion.

CYLINDER LINER FOR AN
OPPOSED-PISTON ENGINE

RELATED APPLICATIONS/PRIORITY

This disclosure includes material related to the disclosure of commonly-owned U.S. application Ser. No. 13/385,127, filed Feb. 2, 2012, and titled "Opposed-Piston Cylinder Bore Constructions With Solid Lubrication In The Top Ring Reversal Zones", which is now U.S. Pat. No. 8,851,029 B2. 10

FIELD

The field includes opposed-piston engines. More particularly, the field relates to a cylinder liner constructed to support sliding movement of a pair of opposed pistons. 15

BACKGROUND

Construction of an opposed-piston engine cylinder is well understood. The cylinder is constituted of a liner (sometimes called a "sleeve") retained in a cylinder tunnel formed in a cylinder block. The liner of an opposed-piston engine has an annular intake portion including a cylinder intake port near a first liner end that is longitudinally separated from an annular exhaust portion including a cylinder exhaust port near a second liner end. An intermediate portion of the liner between the intake and exhaust portions includes one or more fuel injection ports. Two opposed, counter-moving pistons are disposed in the bore of a liner with their end surfaces facing each other. At the beginning of a power stroke, the opposed pistons reach respective top center (TC) locations in the intermediate portion of the liner where they are in closest mutual proximity to one another in the cylinder. During a power stroke, the pistons move away from each other until they approach respective bottom center (BC) locations in the end portions of the liner at which they are furthest apart from each other. In a compression stroke, the pistons reverse direction and move from BC toward TC. 20

A circumferential clearance space between pistons and cylinder liners is provided to allow for thermal expansion. After long hours of operation carbon builds up in this clearance space, on the top land of a piston. Carbon built up on the top land of a piston moving in this space can result in increased friction and ring wear; at worst it can cause ring jacking. In conventional four-stroke, single-piston engines, carbon removal from the top land is typically performed by scraper ring hardware mounted between the top of the cylinder liner and the cylinder head. In an opposed-piston engine, the possible sites for removing carbon are limited. An opposed-piston engine does not include a cylinder head where carbon scraper devices can be located. Liner construction further reduces the possibilities. It is preferable that carbon removal not occur near the BC locations of the pistons, where the ports are located. Carbon debris near the intake port can contaminate charge air entering the bore, thereby degrading combustion. Carbon debris in the vicinity of the exhaust port can be swept into the gas stream exiting the cylinder after combustion, thereby increasing exhaust emissions. It is therefore desirable to remove carbon from the piston top lands within the liner at locations distant from the intake and exhaust ports. 25

Another factor that degrades engine performance throughout the operating cycle of an opposed-piston engine is related to loss of heat through the cylinder liner. Combustion occurs as fuel is injected into air compressed between the piston end surfaces when the pistons are in close

2

mutual proximity. Loss of the heat of combustion through the liner reduces the amount of energy available to drive the pistons apart in the power stroke. By limiting this heat loss, fuel efficiency would be improved, heat rejection to coolant would be reduced, which can allow use of smaller cooling systems, and higher exhaust temperatures can be realized, which leads to lower pumping losses. It is therefore desirable to retain as much of the heat of combustion as possible within the cylinder. 5

An opposed-piston engine cylinder liner constructed according to the present disclosure satisfies the objective of carbon removal, thereby increasing the durability of the engine relative to opposed-pistons of the prior art. An opposed-piston liner construction according to the present disclosure satisfies the objective of heat containment, thereby allowing opposed-piston engines to operate higher heat retention than opposed-piston engines of the prior art. In some aspects, an opposed-piston liner construction according to the present disclosure satisfies both of these objectives simultaneously. 10

SUMMARY

25 A cylinder liner for an opposed-piston engine constructed in accordance with the present disclosure increases durability of an opposed-piston engine by reducing or eliminating carbon build-up on the top lands of opposed pistons contained in the liner. The cylinder liner has a cylindrical wall with an interior surface defining a bore centered on a longitudinal axis of the liner. The bore has a first diameter. Intake and exhaust ports are formed in the cylindrical wall near respective opposite ends of the liner. An intermediate portion of the liner extends between the ends and includes an 30 annular liner portion within which the pistons reach their TC locations. The annular liner portion is defined between first and second top ring reversal planes that orthogonally intersect the longitudinal axis. The first top ring reversal plane is at a first axial position where the topmost ring of a first piston is located when the piston is at its TC location. The second top ring reversal plane is at a second axial position where the topmost ring of a second piston is located when the piston is at its TC location. A liner ring is seated in a 35 portion of the bore contained in the annular liner portion. The liner ring has an interior annular surface with a second diameter that is slightly less than the first diameter. Thus, the liner ring slightly reduces the clearance space between the liner bore and top lands of the pistons. Since the liner ring includes the TC locations of the cylinder bore, the top land of each piston will only traverse the liner ring when the piston approaches and leaves TC. Therefore, the liner ring reduces the clearance where carbon collects so as to remove 40 excess carbon as the top lands pass over the ring. 45

The highest concentration of heat in the cylinder occurs in 50 the annular portion of the liner between the TC locations of the pistons, where combustion takes place. Nearly half of the total heat flux into the liner occurs in this annular portion. Accordingly, construction of the liner ring in such a manner as to yield a high thermal resistance will reduce heat flux 55 through the annular liner portion. 60

BRIEF DESCRIPTION OF THE DRAWINGS

FIG. 1 is a perspective view of a cylinder in accordance 65 with the present disclosure with a section removed to show a pair of opposed pistons disposed in a bore therein between bottom and top center positions.

FIG. 2 is a perspective view of the cylinder of FIG. 1 with a section removed to show a liner ring seated in the bore of the cylinder of FIG. 1.

FIG. 3 is an enlarged side sectional view of an annular liner portion of the cylinder liner of FIGS. 1 and 2 showing the liner ring in greater detail.

FIG. 4 is the view of FIG. 3 rotated axially by 90°.

FIG. 5 is an enlarged side sectional view of a first alternate cylinder liner construction in accordance with the present disclosure.

FIG. 6 is an enlarged side sectional view of a second alternate cylinder liner construction in accordance with the present disclosure.

FIG. 7 is a schematic drawing of an opposed-piston engine 100 with one or more cylinder liners according to this specification.

DETAILED DESCRIPTION

With reference to the drawings, FIGS. 1, 2, and 3 show a cylinder liner 10 constructed in accordance with the present disclosure with a section removed to show a pair of opposed pistons 12, 14 therein between bottom and top center positions. Although not shown, the cylinder liner with the pistons therein would be retained in a cylinder tunnel of an opposed-piston engine, for example in the manner described and illustrated in commonly-owned U.S. application Ser. No. 14/450,572, filed Aug. 4, 2014 for "Opposed-Piston Engine Structure With A Split Cylinder Block." The cylinder liner 10 has a cylindrical wall 20 with an interior surface defining a bore 22 centered on an imaginary longitudinal axis of the liner (represented by the line 24). The bore 22 has a first diameter D_1 . Longitudinally-spaced intake and exhaust ports 28 and 30 are formed or machined near respective ends 32 and 33 of the cylindrical wall 20. Each of the intake and exhaust ports 28 and 30 includes one or more circumferential arrays of openings or perforations. In some other descriptions, each opening is referred to as a "port"; however, the construction of one or more circumferential arrays of such "ports" is no different than the port constructions shown in FIGS. 1 and 2.

As is typical, the piston 12 includes at least one annular ring groove 40 with a piston ring 42 retained therein. The piston 12 has a circular peripheral edge 43 where the piston crown 45 meets the end surface 46 of the piston. An annular uppermost top land 47 of the piston extends between an upper surface 48 of the ring groove 40 and the peripheral edge 43. An imaginary annular top ring reversal plane (represented by the circular line 49) that extends around the bore 22 and generally orthogonally to the longitudinal axis 24 indicates an axial location (with respect to the axis 24) where the upper surface 48 of the top ring groove 40 instantaneously comes to rest when the piston 12 reverses direction and begins to move away from TC. Similarly, the piston 14 includes at least one annular ring groove 50 with a piston ring 52 retained therein. The piston 14 has a circular peripheral edge 53 where the piston crown 55 meets the end surface 56 of the piston. An annular uppermost top land 57 of the piston extends between an upper surface 58 of the ring groove 50 and the peripheral edge 53. An imaginary annular top ring reversal plane (represented by the circular line 59) that extends around the bore 22 and generally orthogonally to the longitudinal axis 24 indicates an axial location (with respect to the axis 24) where the upper surface 58 of the top ring groove 50 instantaneously comes to rest when the piston 14 reverses direction and begins to move away from TC.

An intermediate portion 60 of the liner extends between the ends 32 and 33 and includes an annular liner portion 62 of the cylinder wall 20 within which the pistons 12 and 14 reach their TC locations. The annular liner portion 62 is defined between the first and second top ring reversal planes 49 and 59. As per FIGS. 2, 3, and 4, at least one fuel injector port 63 is provided through the annular liner portion 62 in which a fuel injector nozzle (not shown) is seated when the engine is assembled. In the example shown in these figures 10 two fuel injector ports 63 are provided at diametrically-opposed locations in the annular liner portion 62. A liner ring 70 is seated in a portion of the bore contained in the annular liner portion 62. The liner ring 70 has an interior annular surface 72 with a second diameter D_2 that is slightly less than the diameter D_1 of the bore 22. Thus, the liner ring 70 slightly reduces the clearance between the liner bore 22 and top lands 49, 59 of the pistons 12, 14. Since the liner ring 70 extends between the top ring reversal planes, the top land of each piston will only traverse the liner ring when the piston approaches and leaves TC. Therefore, the liner ring reduces the clearance where carbon collects so as to remove excess carbon as the top lands 49, 59 pass over the liner ring 70. As can be seen in FIGS. 3 and 4, the liner ring 70 also includes 15 one or more ports 71 for passage of fuel into the bore. The ports 71 are aligned with the fuel injector ports 63 in the annular liner portion 62. In a preferred construction for seating the liner ring 70 in the bore 22, the liner 10 includes 20 an annular groove 73 in the portion of the bore 22 contained in the annular liner portion 62. The liner ring 70 is received 25 and retained in the annular groove 73.

The annular liner portion 62 defines space inside the bore where combustion occurs. In order to enhance the thermal resistance of this portion of the liner 10, the liner ring 70 can 30 be made to reduce heat flux through the annular liner portion 62 by elevating its thermal resistance with respect to that of the liner itself. In this regard, the material of which the liner ring 70 is made may be selected for a higher thermal resistance than the material with which the liner is made.

Alternatively, as shown in FIGS. 2 and 3, the liner ring 70 35 may be provided with one or more grooves 74 on its outer annular surface with which to form one or more annular air-filled chambers ("air resistors") 75 with the bore 22. Of course, both thermal management options may be used in 40 constructing the liner ring 70. As a result thermal management is enabled during combustion of a mixture of fuel and air between the end surfaces of a pair of pistons disposed in the cylinder liner when the pistons are near respective top center locations in the annular liner portion of the cylinder liner by impeding flow of heat through the cylinder liner with a higher resistance in the annular liner portion than in 45 the rest of the cylinder liner.

This cylinder liner construction can provide an added 50 structural element where maximum compression and peak cylinder pressures occur and so may eliminate the need for an additional external liner sleeve to provide this support. Furthermore, scraping carbon off of the piston top lands will 55 reduce the occurrences of ring jacking, and thereby improve the durability of an opposed-piston engine. Finally, the liner ring can reduce the heat flow through the cylinder liner, between the top ring reversal locations, where nearly half of the total heat lost into the liner occurs.

The body of the cylinder liner may be made from cast iron, or other suitable material. The liner ring 70 may be 60 made from steel, titanium, or other suitable material such as Inconel, to ensure structural integrity of the cylinder liner in the area of maximum pressures during combustion.

5

The liner illustrated in FIGS. 1-3 may be assembled by attaching the liner ring 70 to the liner 10 either with a mechanical fastener or with an interference fit. For an interference fit, the following steps illustrate a preferred method of constructing a cylinder liner according to this disclosure:

1. The liner is constructed with intake and exhaust ports and the bore 22 is initially honed.
2. The annular groove 73 is formed by machining or etching the bore portion of the annular liner portion 62.
3. The bore 22 is honed after the annular groove 73 is formed.
4. The liner is heated to increase inside diameter D_1 and the liner ring 70 is heated to increase its formability.
5. The liner ring 70 is placed in the center of the cylinder liner over the annular groove 73.
6. The liner ring 70 is swaged into the annular groove 73 by driving tapered mandrels through the center of the liner ring 70 so as to expand the liner ring 70 into the annular groove 73.
7. The liner 10 and the ring 70 are cooled.
8. From either end of the liner 10, punches with the approximate shape of the piston top land profile are driven to the liner ring 70. This will accomplish three goals:
  - a. It will complete the swaging process,
  - b. It will fully embed the liner ring 70 into the annular groove 73.
  - c. It will properly size the inner diameter of the liner ring 70.
9. Form one or more injector ports through the annular liner portion 62 and the liner ring 70.

Alternatively, if the liner ring 70 is formed of a ceramic material, it would be made so that the outer ends of the insert were slightly higher than the body of the insert so that a scraping interference will occur between the insert ends and the piston lands.

A first alternate cylinder liner construction according to this disclosure is shown in FIG. 5. In this construction the liner bore diameter is enlarged slightly by machining from one end of the liner into the annular liner portion 62. This allows the liner ring 70 to be installed directly from the one end of the cylinder without the need to fabricate it with a slightly smaller outer diameter than the bore and then be enlarged by a mandrel to fit into the groove in the annular liner portion. Once the liner ring 70 is secured in the interior of the liner annular liner portion 62, an inner liner sleeve 90 having an interior diameter equal to that of the rest of the cylinder is then installed up to the liner ring 70 and is secured therein. The liner ring could be attached to the cylinder liner with mechanical fasteners or seated therein by means of an interference fit. An interference fit could be accomplished by either super cooling the sleeve, (using liquid Nitrogen as an example), to shrink its outside diameter before placing it in the enlarged bore portion and then letting it reach room temperature. Alternatively, the liner could be heated to increase its inside diameter before inserting the sleeve and then both the liner and the inserted sleeve would be cooled.

A second alternate cylinder liner construction according to this disclosure is shown in FIG. 6. In this construction the liner bore diameter D_1 is enlarged slightly to D_3 by machining from one end of the liner part way into the annular liner portion 62. The bore diameter increases to D_4 for the remainder of annular liner portion 62. As can be seen in FIG.

6

6, $D_1 < D_3 < D_4$. The liner ring 70a is formed with an outside diameter that steps from D_2 to D_3 and is installed in the annular liner portion 62 as shown in FIG. 6. This construction requires pistons with unequal diameters, and also requires that the liner ring 70a have a stepped interior diameter such that in a first portion, the interior diameter is equal to or slightly greater than the diameter of the top land of the first piston and, in a second portion, the interior diameter is equal to or slightly greater than the diameter of the top land of the second piston. One or more air resistors may be formed between the outer surface sections of the liner ring 70a and the respective opposing sections of the bore 22.

FIG. 7 illustrates an opposed-piston engine 100 with three cylinders 101, in which each cylinder comprises a cylinder tunnel 103 in a cylinder block 105 and a cylinder liner 107 according to this specification seated in the cylinder tunnel. Of course, the number of cylinders is not meant to be limiting. In fact, the engine 100 may have fewer, or more, than three cylinders.

The scope of patent protection afforded these and other cylinder liner embodiments that accomplish one or more of the objectives of durability and thermal resistance of an opposed-piston engine according to this disclosure are limited only by the scope of any ultimately-allowed patent claims.

The invention claimed is:

1. A cylinder liner for an opposed-piston engine, comprising:
  - a cylindrical wall with an interior surface defining a bore centered on a longitudinal axis of the liner, the bore having a first diameter relative to the longitudinal axis; intake and exhaust ports formed in the cylindrical wall near respective opposite ends of the liner;
  - an intermediate portion of the liner extending between the ends and including an annular liner portion containing piston top center (TC) locations;
  - the annular liner portion defined between first and second top ring reversal planes extending orthogonally to the longitudinal axis, in which the first top ring reversal plane is at a first axial position where the topmost ring of a first piston is located when the piston is at its TC location, and the second top ring reversal plane is at a second axial position where the topmost ring of a second piston is located when the piston is at its TC location;
  - an annular groove in a portion of the bore in the annular liner portion; and,
  - a liner ring seated in the annular groove, in which the liner ring has an interior annular surface with a second diameter relative to the longitudinal axis that is less than the first diameter; wherein:
    - grooves on an outer annular surface of the liner ring that form one or more air resistors with the bore which act between the liner ring and the bore; and,
    - the liner ring is formed from a material having a first thermal resistance and the cylinder liner is formed from a material having a second thermal resistance less than the first thermal resistance.
2. An opposed-piston engine including one or more cylinders, each cylinder comprising a cylinder tunnel in a cylinder block and a cylinder liner according to claim 1 seated in the cylinder tunnel.
